(57) **CLAIM**

The ornamental design for a watch as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front, right-side, top perspective view of a watch, showing the new design;

FIG. 2 is a front elevational view thereof;

FIG. 3 is a rear elevational view thereof; and,

FIG. 4 is a right-side elevational view thereof.

The broken lines depict boundaries of the claimed subject matter, and thus form no part of the claimed design.
